C. F. GALLAGHER

LUBRICATING CAR JOURNAL BOX

Filed Nov. 5, 1923

Patented Mar. 31, 1925.

1,531,384

UNITED STATES PATENT OFFICE.

CHARLES FRANCIS GALLAGHER, OF MAYFIELD, PENNSYLVANIA.

LUBRICATING CAR-JOURNAL BOX.

Application filed November 5, 1923. Serial No. 672,852.

To all whom it may concern:

Be it known that I, CHARLES F. GALLAGHER, citizen of the United States, residing at Mayfield, in the county of Lackawanna 5 and State of Pennsylvania, have invented certain new and useful Improvements in Lubricating Car-Journal Boxes, of which the following is a specification.

My invention relates to lubricating car journal boxes in which an absorbent body, such, for example, as cotton waste, is used to assist in applying the lubricating medium.

It is a well known fact that many railway accidents occur because of the failure of the 10 oiling devices to adequately lubricate the journals on railway trucks. This results in the production of heated axles and bearings, the effect of which has frequently been to bring about serious accidents.

20 The object of my invention is to provide a lubricating car journal box which will avoid the danger incident to imperfect oiling, which will require much less care and attention, and which will maintain a proper 25 lubrication of the parts to be oiled for longer periods of time without refilling. My invention is of great importance in the 30 operation of ordinary railway trains for the reasons indicated above, but it is particularly useful, however, in the operation 35 of trains at high speed and with few stops.

Other objects will appear as the nature of the invention is better understood and the 40 same consists in the novel form, combination, and arrangement of parts hereinafter 45 more fully described, shown in the accompanying drawings and claimed.

In the drawings, wherein like reference 50 characters indicate corresponding parts throughout the several views:

Figure 1 is a side elevational view of a journal box constructed in accordance with the present invention.

Figure 2 is a longitudinal central sectional view thereof.

Figure 3 is a top plan view of the same, and

Figure 4 is a transverse sectional view taken substantially upon the line 4—4 of 55 Figure 1.

In the form of the invention illustrated, the journal box consists of a main oiling chamber 5 the inner or rear wall of which is provided with the usual central opening 6 as at 6 through which the end of the car journal projects into said chamber 5, the

latter being provided with the usual front inclined hinged lid as at 7. Upon one or more sides of the oiling chamber 5 is formed a lubricant or oil well 8, two such wells 60 being herein shown upon opposite sides of the chamber 5, and each of which is provided with a top filling opening that may be closed air tight by means of a filling plug 9.

65 The sides of the lubricant chamber 5 form the inner sides of the wells 8, and have perforations or lateral openings 10 therein at a point slightly spaced above the bottom 11 of the oiling chamber 5 and communicating 70 with the latter and with the bottoms of said wells, suitable hoods being provided upon the sides of the chamber 5 as at 12 so as to overhang the opening 10 for a purpose 75 which will presently become apparent.

If desired, the plugs 9 may be equipped with suitable handles or wrenches 13 for facilitating their removal or replacement.

In operation, absorbent material, such as 80 cotton waste is placed upon the bottom of the chamber 5 and at the sides thereof so as to partially surround the car journal in the usual manner, the hoods or lips 12 preventing such absorbent material from closing the opening 10, and it being understood 85 that this waste is previously fully saturated with oil so as to practically seal the space directly above the openings 10 within the chamber 5 against the passage of air.

The plugs 9 are then removed, after which 90 the wells 8 are filled with oil, and the plugs 9 then replaced, so as to prevent the entrance of air into the tops of the wells. When this takes place, the lubricant flows by gravity through the openings 10 from the 95 wells 8 into the bottom of the oiling chamber 5 until the same rises to the level indicated in Figures 2 and 4 wherein the oil within the chamber 5 forms a seal for the opening 10 so that the lubricant may not 100 flow to a higher level. The waste is thus maintained at all times in a relatively large body of oil maintained automatically at a constant level, which oil is conveyed by capillary attraction to the car journal in the 105 usual manner. Obviously, as the oil in the bottom of the oiling chamber 5 is used, it is replenished by the reduction of the level of the chamber 5 allowing the oil to flow into the latter from the wells 8 through the openings 10.

As shown in Figure 4, the wells 8 are

2
 preferably of triangular form in cross section with downwardly converging inclined outer walls, so that delivery of all of the oil therefrom into the oiling chamber in an effective manner is insured. The top walls of the oil wells 8 are also preferably outwardly and inwardly inclined so as to permit ready access to the filling openings for filling the wells 8 when the journal box is in position upon the car journal, the inclined arrangement of the top walls of the wells 8 being particularly desirable also when said top walls are below the top wall of the chamber 5 for permitting free operation of the ratchet 13 for removal of the closure plugs 9.

From the above description it will be seen that as the oil is used from the bottom of the chamber 5, it is automatically replenished from the wells 8 by gravity, thereby insuring a constant uniform lubrication of the journal for an extended period.

Minor changes may be made without departing from the spirit and scope of the invention as claimed.

What I claim as new is:

1. A lubricating car journal box including a main oiling chamber provided at one side with an opening adapted to receive a journal, oil wells provided upon opposite side walls of the oiling chamber, the side walls of the oiling chamber being provided with openings which communicate with the lower portions of the oil wells, lips formed upon the side walls of the oiling chamber above the openings therein, disposed downwardly over said openings and extending inwardly of the oiling chamber to restrict the flow of oil and air through the openings in the side walls of the oiling chamber, said lips and the openings in the side walls of the oiling chamber being located below the first mentioned opening in the side of the oiling chamber, and the bottom of the oiling chamber being located below the lower ends of the oil wells, whereby the oil level in the oiling chamber is maintained considerably lower than the oil level in the oil well, because of the vacuum created above the oil in the oil wells as said oil therein recedes to replenish the oil in the oiling chamber.

the openings in the side of the oil chamber and the bottom of the oil chamber being located below the lower ends of the oil wells, whereby the oil level in the oiling chamber is maintained considerably lower than the oil level in the oil well, because of the vacuum created above the oil in the oil wells as said oil therein recedes to replenish the oil in the oiling chamber. 45

2. A lubricating car journal box including a main oiling chamber provided at one side with an opening adapted to receive a journal, oil wells provided upon opposite side walls of the oiling chamber and having downwardly and inwardly disposed outer side walls, the side walls of the oiling chamber being provided with openings which communicate with the lower portions of the oil wells, lips formed upon the side walls of the oiling chamber above the openings 60 therein, disposed downwardly over said openings and extending inwardly of the oiling chamber to restrict the flow of oil and air through the openings in the side walls of the oiling chamber, said lips and the openings in the side walls of the oiling chamber being located below the first mentioned opening in the side of the oiling chamber, and the bottom of the oiling chamber being located below the lower ends of the oil wells, 70 whereby the oil level in the oiling chamber is maintained considerably lower than the oil level in the oil well, because of the vacuum created above the oil in the oil wells as said oil therein recedes to replenish the oil in the oiling chamber. 75

In testimony whereof I affix my signature.

CHARLES FRANCIS GALLAGHER.
